UNITED STATES PATENT OFFICE.

JOSEPH BRASS, OF NEWARK, NEW JERSEY, ASSIGNOR TO DELPARK, INC., OF NEWARK, NEW JERSEY, A CORPORATION OF NEW YORK.

COLLAR AND METHOD OF MAKING SAME.

Application filed April 20, 1922. Serial No. 555,730.

To all whom it may concern:

Be it known that I, JOSEPH BRASS, a citizen of the United States, residing at Newark, in the county of Essex, in the State 5 of New Jersey, have invented certain new and useful Improvements in Collars and Methods of Making Same, of which the following is a specification.

The invention relates to an improvement 10 in collars and method of making same.

The object of the invention is to produce a collar, and more particularly a soft collar, having an improved outer flap or downturned portion, to the end that this part of 15 the collar and especially the corner thereof will present a more pleasing appearance and wear longer without fraying. It has heretofore been the more usual practice in fashioning the corners of the outer flaps of soft 20 collars to fold the two intersecting turned-over edges of the flaps upon each other. This method doubles the thickness of the flap at this point and thus detracts from the smooth appearance the corner of the flap 25 should present. Moreover, when the corners of the flap are fashioned in this manner, it is difficult to prevent them from fraying. This is still the more usual or customary method of fashioning the corners of the 30 flaps, although it has been proposed to truncate the corners of the flaps before the edges thereof are turned over, so that when the edges are turned over and stitched down, the two adjacent cut ends of the turned-over 35 edges will abut each other. This method has proven unsatisfactory because the cut ends of the turned-over edges of the flap tend to unravel and fray. According to the 40 method of the present invention, the thickening of the corners is eliminated and the ends of the turned-over or infolded edges are effectively prevented from fraying. The improved collar and method of making it are more particularly described and pointed 45 out in the following specification and in the appended claims.

In the accompanying drawings is shown the preferred form of the improved collar; and the method of making the same is dia- 50 grammatically illustrated. Fig. 1 is a plan of a soft collar embodying the invention with the outer flap shown opened out; Figs. 2 to 5, inclusive, illustrate the various and progressive stages of the improved method

of forming the corner of the flap of the 55 collar; Fig. 6 is a perspective view of the corner of the flap shown in Fig. 3; and Fig. 7 is a section taken along the line 7—7 of Fig. 5.

The improved collar may in general be con- 60 structed by any usual or preferred method. The collar illustrated in the drawings com- 65 prises a neck band 7 and a downturned por- 70 tion or outer flap 8 which is joined to the top edge of the neck band and is outermost when the collar is in use. The neck band is pro- 75 vided in the lower edge of its middle portion and at both ends with button holes 9 adapting it to be fastened to the shirt of the wearer. The neck band is also provided with the but- 80 ton 10 and the button hole 11 by which the tongue portion 12 of the neck band is se- 85 cured in place when the collar is in use. These features are all old and well-known in collar manufacture.

In constructing the corners of the flap of the improved collar according to the method of the present invention, the entire edge of the flap 8 is preferably provided with a bind- 90 ing tape 14 which overlaps the edge equally on both sides, as clearly shown in Fig. 3. The corners of the flap are then truncated as indicated at 15 in Fig. 2, or the corners may be truncated previous to putting on the 95 tape. The cutting or truncation of the cor- 100 ners should be so done that the angles formed by both the lateral edge 13 and the longitudinal edge 16 with the edge 15 of the corner will be substantially equal. The truncated corners are then folded upon themselves transversely of the truncated edge, as shown in Figs. 3 and 6, and stitched. It will be observed by reference to Fig. 6 that when each truncated corner is folded upon itself, the two adjacent ends 21 and 22 of the edges 16 and 13, respectively, are superposed upon each other and that the stitches 23, by which these superposed ends are held together are as close to the edge 15 as it is mechanically convenient to place them. In making this fold the edges of the corner are moved outwardly (having refer- 105 ence to the outer surface of the flap when the collar is in use) and brought together so that there is a pocket opening outwardly in each corner, as shown in Fig. 6. The next step in the operation is to turn these pockets inside out after the manner shown

in Fig. 4. The pockets now open inwardly or toward the neck band. After the corners have been thus turned, the longitudinal and transverse edges of the flap are then folded 5 inwardly and turned down against the inner surface or surface of the flap (having reference to the surface which lies against the neck band when the collar is in use). The turned-over longitudinal and transverse 10 edges of the flap are held in place by the rows of stitches 17 and 18. Upon the completion of this step of the method, the inner side or surface of the flap presents the appearance shown in Fig. 5.

15 When the pocket formed by the superposition of the adjacent ends of the longitudinal and transverse edges of the collar is turned inside out and the corner is brought to the condition shown in Fig. 5, 20 the line of stitches 23 determines the joint 20 at which the ends of the longitudinal and transverse edges of the flap abut each other when these edges are turned down against the inner surface of the flap. This 25 is clearly brought out in Fig. 7. It will be observed that the material 24, which lies between the line of stitches 23 and the edge or edges 15 of the corner before the pocket at the corner is turned inside out, is tucked 30 under and held against the inner face 25 of the flap. Thus it will be seen that the abutting ends of the turned-over longitudinal and transverse edges of the flap are effectively prevented from fraying or raveling. 35 The middle portion 26 of the outer surface of the corner of the flap is shown in Fig. 7 as bulging outwardly exaggeratedly. This is done for the purpose of clearly illustrating the construction and the relationship of the parts at the corner. As a matter of fact, when the corners of the flap have 40 been constructed as described above and the flap is ironed out, the outer surface of the corners of the flap presents a smooth appearance. 45 This is because the row of stitches 23 is so close to the superposed ends 15 that the material 24 is flattened out and taken up against the turned-over edges of the flap. Thus there is produced a corner 50 for collars, and especially for soft collars, which is more slightly in appearance than the corners as heretofore produced and which with ordinary usage is not likely to become frayed. In fact, it is practically impossible for the corner of the flap to become 55 frayed during the life of the collar.

Having thus described the invention what I claim as new is:—

1. A collar comprising a neck band and an outer flap joined to the neck band, the lateral and longitudinal edges of the flap being bound by a tape and being turned over and folded against the surface of the flap which lies against the neck band when the collar is in use, the adjacent ends of the turned-over 60 edges of the flap being superposed upon each other and held together by a row of stitches, the material between the stitches and these ends lying between the turned-over edges and the inner surface of the flap. 70

2. A collar comprising a neck band and an outer flap joined to the neck band, the lateral and longitudinal edges of the flap being turned over and lying against the inner surface of the flap, the adjacent ends of the 75 turned-over edges being folded under to lie between the edges and the inner surface of the flap so that the folded ends abut each other and means for securing the abutting ends together. 80

3. The method of making collars which comprises constructing a neck band and an outer flap joined thereto, stitching a tape on the lateral and longitudinal edges of the flap, truncating the corners of the flap, making a transverse fold in the corners and stitching it, turning the pockets thus formed inside out, and folding the lateral and longitudinal edges of the flap toward the neck band. 90

4. The method of manufacturing collars which comprises constructing a neck band and an outer flap, truncating the corners of the flap, folding the corners outwardly and transversely of the truncated edge and 95 stitching them, turning the pockets thus formed inside out, and folding the lateral and longitudinal edges of the flap toward the neck band. 100

5. The method of manufacturing collars, 100 which comprises constructing a neck band and an outer flap, truncating the corners of the flap so that the angles formed by the lateral and longitudinal edges of the flap with the truncated corner are substantially 105 equal, folding the corners outwardly and fastening the edges of the corner in superposed relation, turning the pocket thus formed inside out and turning down the lateral and longitudinal edges of the flap 110 against the inner surface of the flap. 115

JOSEPH BRASS.
